CARD DELIVERY APPARATUS

Nelson S. Welk, Athens, Ohio, assignor to The
McBee Company, Athens, Ohio, a corporation
of Ohio

Application December 21, 1940, Serial No. 371,130

5 Claims. (Cl. 271—87)

My invention relates to delivery apparatus for machines of the class described in my copending application Serial No. 352,703.

In that application I have described a stop for card counting machines such as described in my copending application Serial No. 286,570 which illustrates and described a machine for counting cards, checks, loose leaves, etc.

This machine is operated at a very high rate of speed counting accurately as high as 50,000 units or cards per hour.

The machine described in the latter application having to handle so many units in one hour's time necessarily requires special delivery mechanism since the cards leave the machine at such a high velocity.

In order to receive the cards or other units being counted I devised an auxiliary wooden delivery or stacker roll which is carried by a cross shaft which in turn is journaled in arms carried by a shaft which is bolted to the side members of the frame of the machine.

Mounted upon the same shaft are deflector horns adapted to be impinged by the cards which then are guided downwardly under the auxiliary stacker roller and intermediate it and the conveyor belt which rotates the roller and carries the cards to a stacker.

It has been found in practice that it is desirable to have a quick and easy adjustment for this delivery mechanism due to varying conditions such as weight of cards or units, size of same and the varying speeds of the machine.

My invention has for its principal object to provide a quick detachable and adjustable means for supporting the stacker roll carrying mechanism.

My means of accomplishing the foregoing objects may be more readily understood by having reference to the accompanying drawings which are hereunto annexed and made a part of this specification in which:

Fig. 1 is a fragmentary top or plan view, showing only a portion of my counting machine;

Fig. 2 is a side elevation of the same; and

Fig. 3 is a perspective detail view showing my improved support.

Similar reference numerals refer to similar parts throughout the entire specification.

As shown in the drawings the cards (not shown) are discharged from the carrying rollers 1, since these are fully described in my application and form no part of the present invention, specific description thereof is omitted.

The machine is provided with side frames or

panels 2 and 3 which carry the bearings for the various cross shafts. In the rear of the carrying walls is located the stacker roll 4, a shaft 5 is arranged to carry the stacker roll assembly and the deflector horns. This shaft 5 has a pair of collars 8 and 9 slidably mounted on it. One end of arms 10 and 11 are rigidly attached to the collars 8 and 9. Means should be provided for adjustment of the locations of the collars on the shaft. As shown I employ set screws 12 for that purpose so that if it is desirable to use a wider stacker roll on account of a variation in the size of the cards, the collars 8 and 9 and in turn the arms 10 and 11 may be readily adjusted thereto. An axle 13 is mounted in bearings 14 and 15 located in the ends 16 and 17 of the arms 10 and 11. The stacker roll 4 which is preferably made of wood is rotatably mounted on the axle 13. Rotation is imparted to the stacker roll 4 by contact with a conveyor belt 18 which is provided to carry the cards away from the counting machine.

It will be clear from the foregoing description that the stacker roll 4 can be raised or lowered by loosening the set screws 12 so as to adjust the frictional engagement with the conveyor belt 18. Each end of the stacker roll support shaft 5 is mounted in and carried by a metal block 19. These blocks 19 are preferably provided with holes to which are fitted the ends of the shaft 5. They are fixedly secured on the ends of the shaft 5 by means of set screws 20 or in any other suitable and convenient manner. Friction plates 21 and 22 are riveted or welded to the inside of the blocks 19. The lower ends 23 and 24 of these friction plates 21 and 22 are flared outwardly as at 25 clearly seen in Fig. 3. The inner surface of the plates 21 and 22 should be a tight slide fit over the side plates 2' and 3'. The flaring portion 25 being designed to facilitate mounting the stacker roll assembly in position. Deflector horns 26 and 27 are mounted on and carried by the axle 13 which carries the stacker roll 4. Provision is made for the adjustment of these horns by means of a series of holes 30 near the end of the horns. These holes coinciding with the axle 13, so that by removing the nuts 28 and 29 on the ends of the stacker roll axle 13, the deflector horns 26 and 27 may be removed and the ends of the axle inserted in the hole which will bring the horns to the required elevation.

It will be apparent to persons skilled in the art that I have provided a construction which permits the entire stacker roll assembly, including the deflector horns, to be quickly and easily re-

moved or adjusted longitudinally of the machine without requiring the use of any tools at all.

Having described my invention what I regard as new and desire to secure by Letters Patent is:

1. In a counting machine having a frame, means to feed a card, a stacker roller and deflector horns; means to support said stacker roll and deflector horns comprising a shaft, arms secured thereto which support said roller and horns, means at the ends of said shaft, to slidably engage the sides of said frame.

2. In a counting machine having a frame, means to feed a card, a stacker roller and deflector horns; means to support said stacker roll and deflector horns comprising a shaft, arms secured thereto which support said roller and horns, a block secured to each end of said shaft, a plate carried by each block, said plates being adapted to slidably engage the sides of said frame.

3. In a counting machine having a frame, means to feed a card, a stacker roller and de-

flector horns comprising a shaft, arms secured thereto which support an axle which carries said rollers and horns, means at the ends of said shaft, to slidably engage the sides of said frame.

4. In a counting machine having a frame, means to feed a card, a stacker roller and deflector horns; means to support said stacker roll and deflector horns comprising a shaft, arms secured thereto which support an axle which carries said roller and horns, a block secured to each end of said shaft, a plate carried by each block, said plates being adapted to slidably engage the sides of said frame.

5. In a counting machine having a frame, means to feed a card, a stacker roller and deflector horns; means to support said stacker roll and deflector horns comprising a shaft, arms secured thereto which support said roller and horns, means to detachably mount said stacker roll assembly on the side of said frame.

NELSON S. WELK.
